(57) **CLAIM**

The ornamental design for a network device, as shown and described.

DESCRIPTION

FIG. 1 is a perspective view of a network device showing the design.

FIG. 2 is a front elevation view of the network device of FIG. 1.

FIG. 3 is a rear elevation view of the network device of FIG. 1; and,

FIG. 4 is a top plan view of the network device of FIG. 1, with the bottom, left, and right sides of the network device being identical thereto.

The dashed lines shown in the drawings illustrate portions of the network device that form no part of the presently claimed design. The shading lines shown in the drawings represent the approximate three-dimensional contour of the claimed design and are not intended to indicate surface decoration.
